Attorney.

UNITED STATES PATENT OFFICE.

ARTURO BARDELLI, OF MILAN, ITALY.

AUTOMATIC FIREARM.

1,355,378.

Specification of Letters Patent. Patented Oct. 12, 1920.

Application filed April 10, 1919. Serial No. 289,129.

To all whom it may concern:

Be it known that I, ARTURO BARDELLI, residing at 11 Piazza Castello, Milan, in the Kingdom of Italy, have invented new and useful Improvements in Automatic Firearms, of which the following is a specification.

With firearms, as well known, it is advisable to have as little recoil as possible and to keep the barrel perfectly tight until the bullet has left the barrel, to which end the breech and the breech block should be rigidly connected until the said moment.

In guns of the movable barrel type this is readily obtainable, but in fixed barrel guns (whose construction allows of a reduction in the weight) the closure never is absolutely tight unless a quantity of gas is taken off from the barrel, which involves other not irrelevant inconveniences.

The arrangement forming the object of the present invention enables the attainment of the said two results, viz., reduction (if not suppression) of the recoil and absolute tightness of the gun the breech block being opened only after the bullet has left the barrel.

The annexed drawing diagrammatically shows by way of example in longitudinal section an automatic gun fitted with the arrangement according to the invention.

At the barrel muzzle a sleeve C is applied, the sleeve being adapted to slide on the disk D in the direction of the barrel axis. At the moment the bullet leaves the barrel, the gases tend to expand in the chamber C' formed by the sleeve C and disk D, a pressure P being thus set up in the said chamber.

As the barrel is fixed, it is the sleeve that is shifted forward in the direction of the arrow *f* as far as this is allowed by the spring M which limits the strokes of sleeve C and, when the gas expansion is completed, brings the sleeve back into its starting position.

The pressure P set up in chamber C' can be varied within certain limits that may be established in advance by varying the chamber size or by forming gas outlet holes *f'* in the sleeve walls. Thus, not only a very considerable amount of energy is stored up, but at the instant the bullet issues from the muzzle and the arm starts recoiling, a stress in the opposite direction and tending to annul the recoil stroke is

obtained. The arm as a whole will exhibit a greater stability than if there were no sleeve.

If by any suitable method the aperture 60 of the members closing the breech block is caused to be controlled by the forward movement of the sleeve, an absolute closure is obtained inasmuch as the breech and the breech block remain rigidly connected as 65 long as the bullet has not yet left the barrel.

According to the character and type of gun concerned this can be realized in different ways, one of which may be that described hereinafter and illustrated in the annexed drawing.

The breech block O, which is assumed to be cylindrical and similar to that of the Italian 1891 pattern gun, is provided with 75 two openings A in which, when the gun is closed, are lodged the teeth B of two closing members V, or two small wings engaging the teeth of the closing members. Each closing member V consists of a lever pivoted 80 at *p* (the latter may be either a pin or a fixed point of the breech C') and accordingly capable of rocking in the direction S and thus releasing the breech block which can then begin its backward stroke. 85

The closing members however can rock only when the tooth *d* of the sleeve in its movement in the direction *f* comes to bear against the projecting or inclined portion *p'* of the closing members. The springs *m* on the breech C' rock the closing members back into closing position as soon as the sleeve has returned to its resting position when the breech block has not yet completed its out and back trip for 95 removal of the exploded and insertion of the fresh cartridge. The extensions *r* of the closing members acted upon by the springs *m* do not permit of said members going beyond their normal position 100 and eventually hindering the delivery of the fresh cartridge from the band and its introduction into the barrel.

The spring M may also be arranged in the immediate proximity of the sleeve so 105 as to have its fixed point at D instead of at D₁. By so timing the releasing movement of the members B that the pressure exerted by the teeth *d* on the projections *p* commences immediately when the sleeve 110 starts moving or a little later, it results that the pressure P acting on the breech block

and causing its recoil will be increased or diminished. In this way, by utilizing a more or less strong returning spring, a higher or lower bullet velocity will be obtained or, the velocity remaining unaltered, a greater or smaller stress on the various parts and therewith a smaller recoil.

Having now described my invention and how the same is to be carried out, what I claim as my invention is:

1. In an automatic firearm, the combination, with a fixed barrel, a movable breech block and means for locking the breech block in one position; of a sleeve slidably mounted on the barrel and extending the entire length thereof, said sleeve providing an internal gas expansion chamber in communication with the barrel to permit the gases of explosion to collect and expand in said chamber and force the sleeve forward; means on said sleeve for releasing said locking means during the sliding movement of

the sleeve; and a spring for returning said sleeve adapted to be compressed by the forward movement of the sleeve.

2. In an automatic firearm, the combination, with a fixed barrel, and a movable breech block; of spring actuated catches engageable with the breech block to lock the same in one position; a gas actuated sleeve slidably mounted on the barrel and extending the entire length thereof, said sleeve providing an internal gas expansion chamber in communication with the barrel to permit the gases of explosion to collect and expand in said chamber and thereby force the sleeve forward; teeth on the rear end of said sleeve engageable with said catches during the forward movement of the sleeve to release the catches from engagement with the breech block; and a spring for returning said sleeve adapted to be compressed during the forward movement of the rear end.

ARTURO BARDELLI.
